J. H. SCHERMANN

HYDRAULIC SHOCK ABSORBER

Filed April 22, 1924

FIG. 2

FIG. 3

FIG. 4

INVENTOR

John Henry Schermann
By Kay, Totten & Brown,
Attorneys

UNITED STATES PATENT OFFICE.

JOHN HENRY SCHERMANN, OF PITTSBURGH, PENNSYLVANIA.

HYDRAULIC SHOCK ABSORBER.

Application filed April 22, 1924. Serial No. 708,197.

To all whom it may concern:

Be it known that I, JOHN HENRY SCHERMANN, a citizen of the United States, and a resident of Pittsburgh, in the county of Allegheny and State of Pennsylvania, have invented a new and useful Improvement in Hydraulic Shock Absorbers; and I do hereby declare the following to be a full, clear, and exact description thereof.

10 My invention relates to hydraulic shock absorbers and particularly to means for absorbing the momentum of a moving volume of water.

15 The sudden stoppage of water flow in a distributing system, as by the quick closing of a faucet, results in hammerlike shocks that produce objectionable noises and imposes excessive strains upon the pipes.

20 Heretofore, various means have been proposed for taking up these shocks, such as by air chambers communicating directly with the water system and by a tight-fitting movable piston between the air chamber and the water line. In the former case the air chamber becomes filled with water after a time, thus rendering it ineffective to absorb shocks, and in the latter case the construction is expensive, besides which water will eventually find its way past the piston, thus 25 destroying its effectiveness as a shock absorber.

The object of my invention is to provide a structure wherein objections such as the foregoing are eliminated.

35 One form which my invention may take is shown in the accompanying drawing wherein Fig. 1 is a view, partially in elevation and partially in section, of a construction embodying my invention; Fig. 2 is an enlarged sectional view of a portion of the apparatus of Fig. 1; Fig. 3 is a view similar to that of Fig. 2 but showing some of the parts thereof in elevation, and Fig. 4 is a view taken on the line 4—4 of Fig. 2.

45 Referring to the drawings, 5 is a water line to which my invention is connected by means of a T 6. The device includes a tubular chamber 7 having a cap 8 to which a stem or rod 9 is secured by screw threading or otherwise. A spring seat 10 is secured to the lower end of the rod 9, a piston or plunger 11 is slidably supported upon the rod 9 and normally held in mid-position thereon by springs 12 and 13. The spring 50 12 seats against the cap 8 and the upper side of the plunger 11 and the spring 13 fits

between the opposed faces of the cap 10 and the plunger 11.

The piston or plunger 11 fits the cylinder 7 with only sufficient clearance to permit free movement thereof longitudinally of the rod 9 and is provided with a tapered upper surface and a lower surface that is mainly flat although it may be cup shaped somewhat after the manner shown at 14 in Fig. 65 2. The piston 11 is further provided with a plurality of longitudinally disposed, downwardly tapering, grooves 15, to permit the water above the piston to pass to the front thereof when the piston is moved upwardly. While I show a plurality of grooves 15, it will be apparent that under some conditions of operation one groove may suffice.

When the flow of water through the pipe 5 is shut off suddenly, as by a spigot 16, the impact of the moving body of water in the pipe 5 will be transmitted to the lower face of the piston 11. Tests made with the piston 11 mounted in a glass tube, show that the piston will move upwardly under such shocks for a distance of about one-fourth of an inch at times, but may move either more or less, depending upon conditions, and in any event will move upwardly sufficient to absorb the shock to such a degree that the hammerlike noises in the system are eliminated.

From the foregoing description it will be seen that I provide a structure simple and effective in its operation and requiring practically no attention to keep it in proper working order.

What I claim is:

1. The combination with a water line, of a shock absorber comprising a chamber disposed outside of but tapped into said line, and a metallic piston fitting within said chamber and normally disposed intermediate the ends thereof, a communicating passage being provided between the opposite sides of said piston.

2. The combination with a water line, of a shock absorber therefor, comprising a chamber disposed exterior of but communicating with said line, a piston of non-yielding material movable therein, means for yieldingly holding said piston at a predetermined mid-point in said chamber, and means providing communication between the opposite sides of said piston.

3. The combination with a water line, of

2

a shock absorber comprising a chamber communicating with said line, and a piston of non-yielding material fitting within said chamber and normally disposed intermediate the ends thereof, a communicating passage being provided between the opposite sides of said piston, the said piston tapering towards its rear end.

4. The combination with a water line, of
10 a shock absorber comprising a chamber communicating with said line, a plunger fitting within said chamber and normally disposed intermediate the ends thereof, and means
15 for providing communication between opposite sides of the plunger, the said plunger being of tapering form at its rear side and having a substantially flat surface at its

front side, the said flat surface being provided adjacent to its periphery with a rigid annular flange. 20

5. A shock absorber comprising a chamber provided with an opening at one end, a removable cover for the other end of the chamber, a rod carried by said cover and extending longitudinally of the chamber, a 25 plunger slidably supported by said rod, and means for yieldably supporting the plunger at a point intermediate the ends of said chamber.

In testimony whereof I, the said JOHN 30
HENRY SCHERMANN, have hereunto set my hand.

JOHN HENRY SCHERMANN.
